UNITED STATES PATENT OFFICE.

JAKOB SCHAFER, OF NEW YORK, N. Y.

CANDLESTICK.

SPECIFICATION forming part of Letters Patent No. 637,671, dated November 21, 1899.

Application filed November 5, 1898. Serial No. 695,610. (No model.)

To all whom it may concern:

Be it known that I, JAKOB SCHAFER, a subject of the Emperor of Austria-Hungary, residing at New York, in the county and State 5 of New York, have invented new and useful Improvements in Candlesticks, of which the following is a specification.

This invention consists in novel features of construction of a candle stick or holder, as set 10 forth in the following specification and claims and illustrated in the annexed drawings, in which—

Figure 1 is a face view of the candle stick or holder. Fig. 2 is a sectional edge view of 15 Fig. 1. Fig. 3 is a plan view of Fig. 1. Fig. 4 shows a socket-member section. Fig. 5 shows a modification.

In the drawings is shown a multiple-socket candle stick or holder or one having sockets 20 or receivers for more than one candle. A base is shown at 1, and the sockets 2 are connected at intermediate points to the base, a web 3 serving to connect to the base intermediate the sockets, as at points 4, by solder or 25 other connecting means. A practical way is to form the socket member of two sections, each made of sheet metal bent to form flutings or half-sockets, connected to one another by a straight or intermediate web portion.

On superposing these sections the corresponding flutings form sockets 2, and the intermediate or web portions, being secured or soldered together intermediate the sockets, as 30 at points 5, will form a multiple-socket candlestick. In case a candle should burn low in a socket and heat the latter, the solder at 4 or 5, being at some distance from or intermediate the sockets, will not be heated to such a degree as to melt or detach, while if the 40 socket were soldered directly to the base such heated socket might drop or melt loose and fall together with a lighted candle-stump, thus causing accidents. The web or intermediate portion is shown straight; but of course such web can be bent or curved, as 45 seen fit. Such web, for example, could be bent into letter or flower form or into circular or other shape, as required, for decorating or other purposes, and a number or variety 50 of such multiple candle holders could be clustered or arranged as required. The device could be used, for example, as a Christmas-

tree bracket, a web of suitable length and with a suitable number of sockets being arranged or shaped to suit the taste or requirement. 55

In Figs. 1 and 3 the socket member is shown comprising two halves or sections secured together. If desired, the double web can be replaced by a single web, as seen in Fig. 5, 60 a piece of sheet metal being bent to form a complete tube or sufficiently bent to form a socket 2', which will retain a candle, while the intermediate single web 3' will answer the same as the double web 3. For light or cheap 65 work this single-layer structure may be preferred.

The web or connection 3 or 3' could be connected to the base 1 by clips or like fastenings 6; but as it requires time and labor to 70 die or cut the clips and openings and to fit the clips to such openings or cuts into which the clips are to be inserted soldering may be preferred, as the latter allows the use of straight or rectilinear stock, which can of 75 course be otherwise made or shaped or the candlestick mounted on any suitable support, either stationary or movable. The web or connection 3 or 3' is shown unbroken, but could be perforated or made of open or fret 80 work or otherwise, as required, and by suitable machinery.

What I claim as new, and desire to secure by Letters Patent, is—

1. A candlestick, comprising a member 85 bent to form candlestick-sockets with integral web portions between said sockets, and a base to which said integral web portions between the candlestick-sockets are rigidly secured, substantially as described. 90

2. A candlestick comprising a member bent to form sockets with integral web portions between, said web portions being provided with clips or tongues, and a base provided with openings at intervals to receive 95 said clips or tongues, substantially as described.

In testimony whereof I have hereunto set my hand in the presence of two subscribing witnesses.

JAKOB SCHAFER.
